UNITED STATES PATENT OFFICE

OWEN DOUTT, OF CHICAGO, ILLINOIS, ASSIGNEE, BY MESNE ASSIGNMENTS, TO GENERAL SPRING BUMPER CORPORATION, A CORPORATION OF MICHIGAN

GRINDING MACHINE

Application filed April 2, 1928. Serial No. 266,555.

This invention relates to a grinding machine and more particularly to a machine adapted to continuously feed and grind, polish or buff curved bars. An object of the invention is to provide a machine which will feed the bars to the grinding element and which will automatically regulate the pressure holding said bars in contact with the abrasive or polishing element. A further object is to automatically compensate for irregularities in the shape or in the thickness of the bars in the machine. A further object is to provide a work holder to feed curved bars having eyes at their ends, such as bumper bars, to the grinding or polishing mechanism and to automatically regulate the pressure exerted by said bars on the grinding or polishing element. A further object is to provide a work holder for feeding curved bumper bars or similar bars to a polishing or buffing element. A further object is to provide means for readily applying the bars to the work holder and for readily removing said bars therefrom. Another object is to provide a work holder for continuously and automatically feeding bars to a grinding, polishing or burnishing element without the creation of excessive heat at the point of contact with the abrasive or buffing element. Further and more or less limited objects will be apparent from the following description, from the drawings and from the use of the articles covered by the appended claims.

Description of specific embodiments of my invention will be made by reference to the drawings in which Fig. 1 represents a side elevation of a grinding or polishing machine; Fig. 2 represents a plan view of the machine shown in Fig. 1; Fig. 3 represents a detail front elevation of the feed wheel and the grinding or polishing element shown in Figs. 1 and 2; Fig. 4 shows a plan view of the feed wheel shown in Fig. 3; Fig. 5 is a section taken on the line 5—5 of Fig. 3; Fig. 6 represents a detail elevation of the means used at one end of each bar to hold it in place upon the feed wheel; Fig. 7 shows a detailed elevation of a similar means used at the other end of the bar for holding it upon the feed wheel; Fig. 8 shows a front elevation,

with a portion at the top cut away, of a modified form of feed wheel; Fig. 9 shows a plan view of the feed wheel shown in Fig. 8; Fig. 10 is a section taken on line 10—10 of Fig. 8; Fig. 11 shows a detailed side elevation of one of the blocks used to hold the end of the bars upon the wheel shown in Fig. 8; Fig. 12 shows a detailed bottom plan view of the block shown in Fig. 11; Fig. 13 shows a section taken on line 13—13 of Fig. 11.

The general assembly of this machine is similar to that shown in my prior application Serial No. 217,951, filed September 7, 1927, of which machine my present invention is an improvement.

In the drawings the reference character 1 denotes a grinding or buffing element rotated by a motor 2 through a shaft 3. The feed wheel 4 is rotated by a motor 5 through a shaft 6, a transmission 7, a train of gears 8, 8, 8 and a shaft 9 to which the feed wheel is keyed. The feed wheel and its driving mechanism are supported as a unit upon the shelf 10 which is slidably supported from the standards 11, 11, 11, 11 by means of the threaded shafts 12, 12 which may be raised or lowered by turning the shaft 13 having gears 14, 14 keyed thereto which mesh with ring gears (not shown) which are threaded to fit the threads of shafts 12, 12 but which are held against vertical movement on said shafts.

In Figs. 3 to 7 I have shown a feed wheel 4 having recesses 15 and 16 across its periphery to receive the eyes 17 at the ends of a bar 18 which is being fed to the grinding or polishing wheel. Each of the recesses 15 and 16 should be made sufficiently large to allow movement of the eyes therein under the pressure of the wheel 4 and each recess 16 may be made considerably wider to accommodate bars of various lengths.

The bars 18 are held upon the surface of the wheel 4 by means of pins 19 and 20, each extending from a corner of, and supported by, a plate 21 or 22, respectively. The plate 21 is supported from the feed wheel 4 by two bolts 23, 23 having shanks somewhat smaller than the apertures therefor in the said plate,

With this construction the plate 21 may be moved freely within a restricted area and the tensioned spring 24, fastened at its inner end to the feed wheel and at its outer end to the plate 21, resiliently confines the outer end of the plate to hold the bars against the said wheel. The plate 22 is similar to plate 21 except that the slots 25, 25 are elongated in order to give relatively greater movement of the pin 20 along the circumference of the feed wheel and to so accommodate bars of varying lengths. Bolts 23^a, 23^a, of smaller cross section than the width of the slots 25, 25 and a spring 24^a, are used as described in connection with plate 21. Upon the side of the feed wheel opposite that on which the plate 21 is supported, a trigger 26 is pivotally mounted upon the bolt 23 passing through an aperture at its rear end. The forward portion of the trigger is cut down, as shown at 26, to provide a narrowed contact with the pin 19. A spring wire 27, fixed at its rear end to the feed wheel 4, has contact at its forward end with the undersurface of the forward portion of the trigger 25 and exerts a pressure thereon tending to hold the trigger in contact with the pin 19.

An outward pressure is exerted upon the inner surface of the bar 18 by the resiliently mounted rests 28 and 29. Each of these rests is supported from the stem 30 (Fig. 5) having a plunger 31 at its lower end. A casing 32 is threaded into an aperture in, or is otherwise suitably fastened to, the rim of the feed wheel and has an aperture adapted to receive the stem 30 and an enlarged aperture adapted to receive the plunger 31. A coil spring 33, extending between the plunger 31 and the stop 34, holds each rest in a position elevated above the surface of the feed wheel 4. The stop 34 is held in position by a pin 35 through one of various holes 36, 36 so that the pressure of the spring 33 upon the plunger 31 may be regulated by fixing the stop 34 in a suitable position. In the form shown the pressure upon the spring may also be varied by screwing the casing 32 into or out of the aperture in the feed wheel 4, the lock nut 37 being used to hold the casing in the desired position. By this means the normal position of the rests in relation to the surface of the wheel will be raised or lowered.

Pins 38 and 39 are connected to the rests 28 and 29, respectively, intermediate the stems 30, 30. These pins moving in the wells 40 and 41 serve as guides and prevent turning of the respective rests upon their central supports. The outer end 29^a of each rest 29 extends beyond the edge of the feed wheel and is bent downward to provide a slanting guide to facilitate the positioning of the bars upon the rests and the depressing of the rests. The outer surface of each rest 28 and the inner surface of each rest 29 are beveled for a similar purpose.

It is apparent that a single rest and a single tension device could be substituted for the separate units herein shown but the use of the two separate tension devices and two separate rests is preferred where two bars are being handled at the same time since by this means variations in the thicknesses of the two bars will be accommodated. The diameter of the feed wheel and the location of the recesses 15 and 16 and the pins 19 and 20 may be varied to accommodate bars of different curvature and of different lengths. This feed wheel may be used either with one bar or with a plurality of bars upon the same pins, depending upon the shape of the article to be polished or buffed.

The operation of the machine is as follows: After adjusting the height of the shelf 10 and the several tensioning devices on the feed wheel so that the desired pressure will be exerted by the bars upon the grinding or polishing wheel, the motors are started to rotate the feed wheel and the grinding wheel in the same or opposite directions, with the feed wheel preferably operating at a somewhat slower speed than the grinding or polishing wheel. One or more bars may then be applied to the upper portion of the feed wheel by depressing the trigger 25 and slipping the eyes at the ends of the bars over the pins 19 and 20. As the wheel rotates the bars will come in contact with the grinding or polishing wheel and will be depressed thereby against the force of the springs supporting the rests 28 and 29. These springs will result in a constant pressure upon the grinding or polishing wheel regardless of minor variations in the thickness of the bars. After the bars have passed the grinding element they may be removed by pressing trigger 25 and slipping the bars off of the pins. The operation may then be repeated or, if desired, the same bars may be left on the wheel for more than one rotation.

The spring tension devices are of greatest importance in the continuous automatic grinding or polishing of bars of spring steel such as those used for bumper bars. In grinding such bars great care must be taken to avoid overheating the bars at the points of contact with the grinding element and thus changing the temper of the bars. By my invention I have provided a machine in which the bars may be continuously and automatically ground or polished without the generation of excessive heat at the points of contact of the grinding or polishing element with the bars.

In the modification of my invention shown in Figs. 8 to 13 the feed wheel is made up of a metal pulley 44 having a cylindrical rim and suitable spokes 45 supported from a central axle housing. The bars 46 to be polished or buffed are supported upon the peripheral surface of the feed wheel and are held there

by spacers 47 which may be varied in their dimensions to accommodate bars of different length and bars having eyes at their ends of different diameter. The spacers 47 are fastened to the rim of the wheel 44 by set screws 48 passing through the rim of the wheel and threaded into the said spacers or by other suitable means. Each side of each spacer is provided with a curved recessed portion 49 adapted to enclose a portion of an eye at an end of a bar and to prevent outward movement of the same. The forward end of the recessed portion 49 is slightly flared to facilitate the insertion of the ends of the bars, and a wall 50 is provided at the rear side of the spacer 47 to act as a stop for the bars. The pointed pins 51, extending through and movable in apertures in the rim of the feed wheel, and resiliently supported by spring metal arms 52 connected to the inner side of the rim at a distance from the said aperture, provide convenient means for resisting the unintentional removal of bars from the feed wheel during the polishing or buffing operation.

One or more arcuate bars having eyes at their ends may be applied to a section of the surface of the feed wheel by depressing pins 51, 51 against the resilient resistance of the spring 52, and advancing the eyes at the ends of the bars into recessed portions in the spacers 47, 47. After the buffing operation is completed the bars may be removed by again depressing the pins 51, 51 and withdrawing the bars from the recesses 49, 49. It is desirable in this modified form of my invention that the spacers be so shaped as to make a smooth curve between the adjacent ends of two consecutive bars. Such arrangement is not essential to my invention but it will prevent the wheel from cutting into the bars as the latter come in contact with the wheel. The diameter of the wheel and the width of the spacers 47 may be varied to accommodate bars of different curvature and of different length. One or more bars may be applied to the wheel for buffing at the same time, the number of said bars depending upon their width relative to the width of the feed wheel and the grinding element.

In the operation of my grinder the shelf 10 may be raised or lowered to accommodate different sizes of grinding, polishing or buffing wheels. It is apparent that one or several narrow bars could be fed to the wheel at the same time and that the number of pressure regulating devices may be varied to accommodate more or less bars upon the periphery of the wheel.

In the use of my invention I prefer to use the feed wheel first described for grinding or polishing and to use my modification for buffing, where the heat generation is not so great. It is apparent, however, that either feed wheel could be used for a grinding, pol-

ishing, or buffing operation if proper precautions are taken in regulating the speed and direction of the wheels and the pressure upon the wheels of the articles fed thereto. It is not intended therefore to limit the use of my feed wheel to the particular application in connection with which it has been described and where the term grinding, polishing, or buffing is used it is not intended to restrict the scope of the invention to such specific operation.

Having thus described my invention, what I claim is:

1. In a feed wheel for supplying curved bars having eyes at their ends to a grinding or buffing element, the combination of means carried by said wheel and contacting with said eyes for retaining said bars upon said wheel, and resiliently actuated means for retaining said eyes in contact with said first mentioned means.

2. A feed wheel comprising resilient means carried by said wheel for resisting movement of work from the periphery thereof, and resilient means for resisting movement of said work toward said wheel.

3. A feed wheel for a grinding or buffing machine comprising means carried by said wheel for holding work on the periphery thereof, and resiliently actuated means for regulating the pressure of said work upon the grinding or buffing element.

4. A work feeder for feeding bars to a grinding or buffing machine, comprising a wheel carrying means for resiliently retaining the ends of said bars, and resilient means intermediate the ends of said bars for resisting movement of said bars toward said wheel.

5. A work holder comprising a wheel carrying means adapted to retain bars adjacent the periphery of said wheel, means adapted to resiliently resist movement of said bars toward said wheel, the said last mentioned means comprising separate rests adapted to bear upon each bar, and a resilient support for each rest carried by said wheel.

6. In a feed wheel for a grinding or buffing machine, the combination with means for retaining said bars upon the surface of said wheel, of resilient means for resisting movement of said bars toward said wheel, said resisting means comprising a rest having a single support resiliently connected to said wheel, and a guide projecting from said rest and adapted to move in an aperture in said wheel.

7. In a feed wheel for a grinding or buffing machine, the combination with resiliently actuated means adapted to retain the ends of articles to be ground or buffed, of resiliently actuated means intermediate the ends of said articles for resisting movements thereof toward said wheel, said resisting means comprising a plate adapted to bear upon the undersurface of said article, said plate being ac-

tuated through a shaft and plunger connected therewith by a spring between an adjustable stop and said plunger.

8. A feed wheel for a grinding or buffing machine comprising a wheel adapted to carry the work upon its peripheral surface, resiliently actuated means carried by said wheel for holding the work thereon, said means being adjustable for varying lengths of work, and resilient means for resisting movement of said work toward the surface of said wheel.

9. A work feeder for a grinding or buffing machine comprising a wheel adapted to support the work on its peripheral surface, and means carried by said wheel for resiliently retaining said work on the surface of the wheel.

10. A work feeder for supplying bars having eyes at their ends to a grinding or buffing element, said feeder comprising a wheel adapted to carry said bars on its peripheral surface, pins adapted to be positioned in the eyes at the ends of the bars and supported by a plate fastened to said wheel so as to allow limited movement relative thereto, and resilient means for resisting outward movement of said plate.

11. A work holder for supplying bars having eyes at their ends to a grinding or buffing element, said holder comprising a wheel adapted to carry said bars on its peripheral surfaces, recesses across the surface of said wheel adapted to receive the eyes at the ends of the bars and to allow movement thereof therein, pins adapted to be positioned in the eyes at the ends of the bars and supported at one end by plates fastened to said wheel so as to allow limited movement relative to said wheel, and resilient means for resisting outward movement of the portion of said plate to which said pin is fastened.

12. A feed wheel for a grinding or buffing machine comprising a wheel having a recessed portion in its peripheral surface adapted to receive an end portion of a bar to be ground or buffed, resiliently actuated means carried by said wheel for holding the said end portion of the bar in said recess, and resiliently actuated means for resisting movement of said bars toward said wheel.

13. In an abrading or grinding machine the combination with a grinding element, of a rotatable feed means adjustably mounted relative to said grinding element, said feed means comprising a wheel adapted to carry bars upon its peripheral surface, spring actuated means carried by said wheel for holding said bars on said wheel, and spring actuated means for resisting movement of said bars toward the periphery of said wheel.

In testimony whereof, I hereunto affix my signature.

OWEN DOUFT.
